UNITED STATES PATENT OFFICE.

EDWARD N. JACOBI, OF MILWAUKEE, WISCONSIN, ASSIGNEE, BY MESNE ASSIGNMENTS, TO BRIGGS & STRATTON CORPORATION, OF MILWAUKEE, WISCONSIN, A CORPORATION OF DELAWARE.

DOOR LATCH FOR AUTOMOBILES.

Application filed June 2, 1924. Serial No. 717,333.

This invention has for its object to provide a door latch for use on automobiles and the like which will be less expensive to manufacture, although as durable and efficient as latches now in general use.

Another object of the invention is to provide a latch construction which will have certain advantages simplifying its manufacture and assembly, as well as reducing the cost of production.

Another object of the invention is to provide a door latch of this character which will serve either as a right-hand latch or a left-hand latch.

Another object of the invention is to provide parts of sheet metal construction throughout and springs of the coiled spring type.

With the above and other objects in view the invention consists in the door latch as herein claimed and all equivalents.

Referring to the accompanying drawings, in which like characters of reference indicate like parts in different views,

Fig. 1 is a rear view of a door latch constructed in accordance with this invention;

Fig. 2 is a similar view thereof with the cover-plate sectioned;

Fig. 3 is a sectional view on the plane of line 3—3 of Fig. 2;

Fig. 4 is a sectional view on the plane of line 4—4 of Fig. 2;

Fig. 5 is a view similar to Fig. 2 showing the latch in its retracted condition, and

Fig. 6 is a sectional view on the plane of line 6—6 of Fig. 5.

In these drawings, 10 indicates a frame-plate having its end bent to form the usual door-jamb-fitting flange 11, through which the pivoted latch-bolt 12 projects to engage the keeper-plate, not shown, in the door-jamb. In the present instance the latch-bolt 12 is formed of heavy sheet metal pressed to shape and pivotally mounted on a bearing bracket

13 formed by a piece of sheet metal folded on itself and riveted to the frame-plate and forming spaced trunnion bearings to receive the ends of a pin 14 passing through the sides of the bolt and fastened in place by having lugs pinched up thereon, as shown. No careful machining or fitting is necessary in assembling the bolt in the frame-plate for it has

no engagement with the plate near its fulcrum, being instead limited in its outward movement by the engagement of a stop flange 55 15 formed at its outer edge with the edge of the opening of the frame-plate, as seen in Fig. 4.

Another pin 16 passing through the side walls of the bolt forms a pivotal connection 60 for the bolt-operator 17, which has its intermediate portion bent around said pin. It will be noted that the pin 16 lies back of the flange 11 of the frame-plate and consequently its ends do not have to be dressed flush with the sides of the bolt in order to avoid engagement with the edges of said opening. The ends of the bolt-operator 17 are rearwardly curved so that the operator forms a yoke-like member and these ends bend downwardly 70 into bearing contact with the frame-plate, as seen in Fig. 3. In the movements of the operator for swinging the bolt, these ends slide along the surface of the frame-plate and are guided in their movements by having projections 18 thereon forming guide lugs fitting in slots 19 of the frame-plate. The engagement of these projections with the ends of the slots forms a stop for limiting the movement of the bolt-operator, as seen in Fig. 6.

The roll-back for engaging either of the bent ends of the bolt-operator 17 consists of two plates of sheet metal 20 and 21 electrically riveted together by spot-welding and these plates are pressed to form a central hub 85 member 22 fitting in an opening of the frame-plate and in a corresponding opening in a cover-plate 23 which is secured to the frame-plate but spaced therefrom in the manner shown in Fig. 3. That is, the cover-plate has top and bottom flanges bearing against the frame-plate with ears 24 projecting through slots of the frame-plate and bent over. The roll-back is thus rotatably mounted between the frame-plate and the cover-plate, suitable shoulders being provided on it to bear against these plates, as seen in Figs. 3 and 4, whereby it is firmly held in its bearings and at its ends it is provided with the square openings 25 to receive the square handle rod 26, as usual. 100 The oppositely extending shoulders of the roll-back engage the bent ends of the bolt-operator 17, as usual, so that when turned in either direction the bolt will be withdrawn.

To give spring pressure to the bolt, coiled springs 27 are housed within the cover-plate and bear on the ends of the bolt-operator. In detail each spring is confined between the connecting flange of the cover-plate and a flange 28 bent up from the frame-plate and is seated at one end against a flange 29 bent down from the cover-plate, while its other end is confined within a spring seat cup 30, which is centered on the end of the bolt-operator 17 by having a central recess or opening fitting on a lug 31 struck up on the end of the bolt-operator, as best seen in Fig. 2.

To return the roll-back to its normal position after being turned in either direction for operating the bolt, its hub is surrounded by a coiled spring 32 with its two ends engaging the opposite edges of an upstanding arm 33 on the plate 21 of the roll-back and also engaging the opposite edges of a downwardly extending stop 34 on the cover-plate. Thus when the roll-back is turned in either direction by the handle to withdraw the bolt, as seen in Fig. 5, the arm 33 carries one end of the spring 32 away from the other, which is held in place by the stop 34 so that the tension of the spring will return the roll-back to its normal position when the handle is released.

To prevent the coiled spring 32 from bearing against the cover-plate and to prevent it from springing off of the hub of the roll-back during assembly a light sheet metal flanged collar 35 is forced onto the hub of the roll-back, as seen in Fig. 4.

From the foregoing the operation of the latch will be understood and it will be appreciated that, aside from the reduction in cost of manufacture due to the use of sheet metal parts with coiled springs, both for the roll-back and for the latch-operator, manufacturing economies are obtained by the avoidance of the use of a bolt stop dependent upon engagement with the frame-plate close to its fulcrum, for with the distant stop flange 15 the positioning of the bracket 13 does not have to be accurately determined. Also all machine work on the bolt is obviated and there is no necessity for grinding off the ends of the pin 16 since it does not enter the opening in the frame-plate. Also the bolt-operator does not require an open bearing engagement with the pin 16 to permit of disconnection for with the pin 16 at the rear of the frame-plate it may be passed through the end of the operator as a part of the assembly operation, which was not possible when the ends of said pin had to be machined to prevent engagement with the edges of the opening in the frame-plate. Also the part of the bolt-operator through which the pin 16 passes may be substantially equal in width to the recess or opening in the bolt, avoiding the necessity for lateral guides.

The use of coiled springs instead of bent

wire springs as usual is not only an economy in manufacture, but increases the durability of the latch and avoids the obstruction to the provision for uniformly positioned screw openings 36 at the top and bottom edges of the frame-plate, whereby the same latch may be used for either right or left-hand door.

What I claim as new and desire to secure by Letters Patent is:

1. A door latch for automobiles and the like comprising a frame-plate bent to form an angular jamb-fitting flange having an opening therethrough, a bearing bracket separate from the frame-plate but attached to the back thereof, a bolt member pivotally mounted in the bracket near the angle between the flange and the frame plate and adapted to swing through the opening, a lug on the outer edge of the bolt to engage the edge of the opening, a pin through the bolt back of the flange, and a spring-pressed operating member pivotally mounted on said pin between the sides of the bolt.

2. A door latch for automobiles and the like comprising a frame-plate having an angular jamb-fitting flange with an opening through the flange, a bearing bracket separate from the frame-plate and secured thereto, a bolt member pivotally mounted on the bracket near the angle between the flange and the frame-plate and projecting through the opening, and a lug on the outer edge of the bolt engaging the edge of the opening.

3. A door latch for automobiles and the like comprising a frame-plate having an angular jamb-fitting flange with an opening through the flange, a bearing bracket secured to the frame-plate at the back thereof consisting of a metal plate folded on itself and forming spaced trunnion bearings, a pin fitting in the spaced trunnion bearings, a sheet metal bolt member having parallel sides mounted on the pin between the trunnion bearings and adapted to swing through the opening of the flange, a pin passing through the parallel sides of the bolt member back of the flange, and an operating member pivotally mounted thereon within the bolt member.

4. In a door-latch for automobiles and the like, a frame-plate, a bracket member thereon, a bolt pivotally mounted on the bracket member and projecting through an opening in the plate, a stop on the outer edge of the bolt for engaging the edge of the opening of the plate, a pin passing through the bolt behind the frame-plate, and a bolt-operator engaging said pin and being of a width substantially equal to the width of the recess of the bolt so as to require no lateral guides.

5. In a door-latch for automobiles and the like, a roll-back comprising two sheet metal plates spot welded together with their edges forming bolt-operator engaging shoulders and shaped to form complementary parts of a hub, a frame-plate and a cover-plate having

said hub journaled therein, one of said plates being deeper than the other to form a spring barrel, a coiled spring surrounding said spring barrel, and a ring fitting on the spring barrel and engaging the coiled spring.

5 6. In a door-latch for automobiles and the like, a roll-back formed of two pieces of sheet metal spot-welded together to produce bolt-operator engaging shoulders and each 10 pressed into cylindrical oppositely extending projections to form a hub, a frame-plate and a cover-plate having the hub journaled therein, a coiled spring surrounding the hub, an arm on one of the roll-back plates extending 15 between the ends of the coiled spring, and a stationary stop also extending between the ends of the coiled spring.

15 7. In a door-latch for automobiles and the like, a roll-back formed of plates of sheet metal spot-welded together to produce bolt-operator engaging shoulders, each plate being pressed to a cylindrical shape to form a hub, a frame-plate and a cover-plate having the hub journaled therein, a coiled spring 20 surrounding the hub with its ends embracing between them a projection from the roll-back and a projection from the cover-plate, and a flanged collar fitting on the hub and engaging the coiled spring.

25 8. In a door-latch for automobiles and the like, a frame-plate, a cover-plate secured thereto, a roll-back journaled between the frame-plate and the cover-plate, a bolt pivotally mounted on the frame-plate, a bolt-operator connected with the bolt and having 30 bent ends bearing on the frame-plate and engaged by the roll-back, and coiled springs bearing on the bent ends of the bolt-operator.

35 9. In a door-latch for automobiles and the like, a frame-plate, a cover-plate secured thereto, a roll-back journaled between them, a bolt pivotally mounted on the frame-plate, a bolt-operator connected thereto and having 40 bent ends bearing on the frame-plate, lugs projecting from the bent ends of the bolt-operator, spring seat cups having openings fitting on said lugs, and coiled springs with their ends fitting in said spring seat 45 cups and bearing against the cover-plate respectively.

50 10. A door-latch for automobiles and the

like comprising a frame-plate having a door-jamb flange, a pivot bracket secured thereto, a sheet metal bolt pivotally mounted 55 on the pivot bracket and projecting through an opening in the flange of the frame-plate, a stop flange on the outer edge of the bolt engaging the edge of the opening of the frame-plate, a pin passing through the side 60 walls of the bolt behind the flange of the frame-plate, a bolt-operator fitting on said pin and of a width approximately equal the width of the recess of said bolt, said bolt-operator having its forked rear ends bent 65 to bear on the frame-plate, lugs projecting from said ends of the operator and traveling in slots of the frame-plate, a cover-plate secured to and spaced from the frame-plate, coiled springs confined between the cover- 70 plate and the bent ends of the bolt-operator, a roll-back formed of two pieces of sheet metal spot-welded together to form shoulders for engaging the bent ends of the bolt-operator and being pressed to cylindrical 75 shape to form a hub journaled in the frame-plate and the cover-plate, a coiled spring surrounding the hub, and projections on the roll-back and on the cover-plate respectively fitting between the ends of the coiled spring 80 surrounding the hub.

11. In a door latch for automobiles and the like, a roll-back having bolt operator engaging shoulders and a hub, a frame plate and cover plate having the hub journaled 85 therein, a coiled spring surrounding the hub, an arm on the roll-back extending between the ends of the coiled spring and a stationary stop also extending between the ends of the 90 coiled spring.

12. In a door-latch for automobiles and the like, a frame-plate, a cover-plate secured thereto, a roll-back journaled between the frame-plate and the cover-plate, a bolt pivotally mounted on the frame-plate, a bolt-operator connected with the bolt and having 95 bent ends bearing on the frame-plate and engaged by the roll-back, guide lugs projecting from the bent ends of the bolt-operator and traveling in guide slots of the 100 frame-plate, and coiled springs bearing on the bent ends of the bolt-operator.

In testimony whereof, I affix my signature.
EDWARD N. JACOBI.
